UNITED STATES PATENT OFFICE.

GENJI NAGAI, OF TOKYO, JAPAN.

KNOCKDOWN PACKING-BOX.

1,388,366.

Specification of Letters Patent. Patented Aug. 23, 1921.

Application filed April 1, 1920. Serial No. 370,526.

To all whom it may concern:

Be it known that I, GENJI NAGAI, subject of Japan, residing at No. 37 Nagasaki Machi, Azabu Ku, Tokyo, Japan, have invented new and useful Improvements in Knockdown Packing-Boxes, of which the following is a specification.

This invention relates to a box for packing goods, constructed and fastened together without using any nail. The object of this invention is to obtain a packing box which is strong but can very easily be taken to pieces, and which can be safely sealed so that unauthorized opening can effectively be prevented.

The accompanying drawings show a box embodying my invention, in which—

Figure 1 is a front view,

Fig. 2 is a plan view, partly sectional, 20 Fig. 3 is a sectional plan view of a corner of the box,

Fig. 4 shows part of inner face of a plank forming a longer side, and

Fig. 5, part of inner face of a plank forming a shorter side,

Figs. 6 and 7 are enlarged and oblique view of latching devices shown in Figs. 3 and 4, and

Fig. 8 is an oblique view of part of one of 30 bolts which fasten the bottom and lid.

To describe my invention fully reference being had to the accompanying drawings, (1) (1) are planks forming the longer sides and (2) (2) are those forming the shorter 35 sides. (3) is the lid and (4) the bottom.

The four sides are fastened together by means of a special kind of latches, and are then placed between the bottom and the lid which are fastened by means of bolts. Al- 40 though the sides are latched together by a very simple means, the whole is so constructed that they cannot be taken to pieces unless after the removal of the lid.

The device for fastening the sides is as 45 follows:—

Nail metal pieces (6) to side planks (2) (2) on the inside at any desired places on the edges which are to be joined to side planks (1) (1). The heads of the metal pieces (6) (6) are bent at right as at (5), and project a little out of the edge of the side planks. On the inside of the side planks (1) (1) at places corresponding to the metal pieces (6) (6) are nailed metal plates (9) (9) each of which is perforated with a hole (7) to receive the head (5) of a metal piece

(6). The hole (7) is narrowed downward as at (8), the narrow part being just wide enough to admit the metal piece (6). The side planks (1) (1) are hollowed out under 60 the metal plates (9) (9) as at (10) to obtain spaces for the heads (5) of the metal pieces (6) to move in.

Now, if we insert the heads (5) of the metal pieces (6) into the corresponding holes 65 (7) (7) of the metal plates (9) (9), and push down the planks (2) (2), the metal pieces (6) (6) will get into the slits (8) (8), and the heads (5) (5) will be firmly caught by the plates (9) (9), and the body of a box 70 is constructed.

The lid and bottom are strengthened by cross-pieces (11), and so are the side planks (1) (1). The cross-pieces of the lid and bottom are cut off at their both ends as at (12) 75 (12), and the notches (12) thus formed are lined with metal plates (13). The bottom of the notches (12) and the lid and bottom are bored through to receive bolts (14).

The body of the box constructed as afore- 80 said is placed on the bottom, the bolts to fasten the bottom and the lid being within the side planks (1) (1), and when it is packed with goods the lid is placed thereon and fastened screwing down nuts (15). At 85 the upper end of each bolt (14), just above the nut (15) there is a hole, through which the cord is to be passed and sealing made in any desired manner. Thus, it will be im- 90 possible to open the box without breaking the seals.

According to my invention, it is preferable to make the planks (2) forming the shorter sides a little broader than the planks forming the longer sides, because if all the side planks are of the same breadth, when the lid and bottom are tightly fastened there is tendency of 95 their curving out, and thus the side planks (2) will not be fastened as tightly as the side planks (1).

I wish it to be understood that modifications may be introduced into this invention without departing from the spirit thereof. For instance, in the devices for latching the side planks together, the metal piece may not be a metal plate having its head bent at right angle, but any enlargement or projection will do for such head with a corresponding hole in the metal plate (9) which would admit the head and then catch it. So also, 105 the device for fastening the lid and the bottom may be other than the one herein de- 110

scribed, the main point of this device being to tighten the bolts within notches so that the bolt ends do not project beyond the box surface.

5 To sum up, my box is easy to construct and also very easy to take it into pieces, and as no nail is used, it can be opened without damaging any part of it. And as it can be put to pieces very easily and without any
 10 10 damage to it, it can be used for transportation purpose over and over again. Moreover, as it can not be opened without unscrewing the nuts of the bolts and as it is sealed above the nuts, there is no fear of its being opened
 15 15 by any unauthorized person. Further as the bolt ends and nuts thereon do not project beyond the box surface, they being contained within notches, no inconvenience will be felt in handling it, nor no unnecessary space will
 20 20 be occupied in piling a number of such boxes.

I claim:

1. A packing box constructed without using any nails characterized by fastening with metal pieces from inside, the four side
 25 25 planks in such a way that the side planks can easily be taken to pieces but not from the outside; placing the body of the box thus formed between a lid and a bottom, both of which have several notches at their
 30 30 edges; lining said notches with metal plates through which bolts are passed from the bottom to the lid along the inner sides of side planks; and securing the bolt ends with nuts so that the bolt ends and the nuts
 35 35 screwed thereon are contained within the notches and can be sealed therein, substantially as and for the purposes hereinbefore set forth.

2. A packing box constructed without using any nails characterized by fixing metal fittings having a head such as (6) or the like to a pair of side planks at places where they are to be connected with the other pair, and at the edges of the said other pair at
 45 45 places corresponding to the metal fitting (6), metal fittings such as (9) or the like, each of which has a hole (7) to receive the head of the metal fitting (6), the said hole (7) further extending in a slit as at (8); inserting the heads of metal fittings (6) into the holes (7) corresponding thereto and causing the metal fitting (6) to be caught at slits

(8); securing the body of the box thus formed between a lid and a bottom, substantially as and for the purposes hereinbefore 55 set forth.

3. A packing box constructed without using any nails characterized by detachably connecting the four side planks, the two shorter of which being a little higher than 60 the two longer side planks, with metal pieces from inside in such a way that they cannot be taken apart except from the inside, thus forming the body of box; securing the body thus formed between a lid and a bottom, both 65 of which having notches; and lining the said notches with metal plates through which bolts are passed from the bottom to the lid along the inside of the box and secured with nuts in such a way that the bolt heads and 70 nuts screwed thereon are contained in the said notches, substantially as and for the purposes hereinbefore set forth.

4. A packing box constructed without using any nails characterized by forming the 75 body of box by detachably connecting at four edges the longer side planks with the shorter side planks which are a little broader than the former; securing the body of box thus formed between a lid and a bottom, both 80 of which are provided with cross pieces having at their two ends notches; lining the said notches with metal plates through which are passed bolts from the bottom to the lid along the inner side of the box; and securing 85 the heads of the bolts with nuts in the said notches so that nothing projects out of the box surface, substantially as and for the purposes hereinbefore set forth.

5. A knockdown packing box comprising 90 four sides, a top and bottom engaging the top and bottom edges of said sides, means operative from the exterior of the box for securing the top and bottom together and to the sides, and means connecting the ends of 95 the sides, entirely concealed from the exterior of the box and detachable to permit the sides to be taken apart, said last named means being inoperative from the exterior of the box without removing said top or bottom.

In testimony whereof I have signed my name to this specification.

GENJI NAGAI.
